UNITED STATES PATENT OFFICE

119,179

DESIGN FOR A DRILL POINT SHARPENER

Edward Dion, New Bedford, Mass.

Application December 16, 1939, Serial No. 88,952

Term of patent 14 years

To all whom it may concern:

Be it known that I, Edward Dion, a citizen of the United States, residing at New Bedford, in the county of Bristol and State of Massachusetts, have invented a new, original, and ornamental Design for a Drill Point Sharpener, of which the following is a specification, reference being had to the accompanying drawing, forming part thereof.

Figure 1 is a side elevational view of a drill point sharpener showing my new design.

Figure 2 is a left hand end elevational view thereof.

Figure 3 is a top plan view thereof.

Figure 4 is a bottom plan view thereof.

I claim:

The ornamental design for a drill point sharpener, as shown.

EDWARD DION.
